CAN, BOX, CANISTER, AND THE LIKE

John Francis Crowley, London, England

Application August 24, 1932, Serial No. 630,302,
and in Great Britain August 26, 1931

3 Claims. (Cl. 220—40)

This invention relates to hermetic or vacuum closures for jars, cans, boxes, canisters or the like, which are hermetically sealed under a vacuum, and are intended for containing and preserving foods or other substances.

The invention further relates to closures in which the container is closed by a cover or cap having a depending flange or skirt which is adapted to fit over a flange on the top or mouth of the container when the cover is applied, and in which an elastic jointing-ring is compressed between a horizontal flange on the cover, and a horizontal shoulder or flange on the body of the container when the container is closed.

15 Closures for jars, bottles, cans or the like articles are known in which a cover or cap fits upon the mouth of the jar or the like by means of a bayonet joint or by means of partial threads to compress a rubber packing ring lying between 20 the cap or cover and a horizontal flange on the jar or the like.

According to the present invention, a jar, can, box, canister or the like comprises a container-part and a cap-part where both parts are of 25 metal, or where one part is of rigid material, such as glass; one part having a horizontal flange adapted to receive an elastic packing ring and having an upstanding flange provided with a number of vertical spaces leading into a partial 30 or complete circumferential groove immediately above said horizontal flange, which spaces co-operate with pips or projections on the other part, which may either freely pass into said spaces, or alternately may frictionally hold upon 35 the full diameter of the upstanding flange of the first-named part, adjacent said spaces, or again may pass into the partial or complete circumferential grooves.

The invention is more particularly described 40 with reference to the accompanying drawing in which:—

Figure 1 is an elevation partly in section of a canister according to the present invention, with cap.

45 Figure 2 is a sectional view of the parts on an enlarged scale in the vacuumizing position.

Figure 3 is a plan view of the body alone of Figure 1.

Figure 4 is an elevation partly in section of a 50 modified form of construction.

Figure 5 is a plan view of a further modified form of construction.

A can body 1 has its upper edge flared outwardly at an angle as at 2, and then bent inwardly as 55 at 3 to provide a ledge for the reception of a

rubber packing ring 4, which has a pull-out tab 5. It will be seen that this packing ring 4 lies on a horizontal flange 3, which overlaps inside and outside the canister to equal extent. A groove 6 lies at the base of a vertical flange to partly accommodate the ring 4.

A number of axial grooves 8 are provided spaced around the flange or neck portion 7 to co-operate with pips 9 formed upon the cap 10, the lower skirt or rim of which is flared outwardly to provide a horizontal ledge 11 adapted to bear upon a rubber ring 4 on the ledge 3.

Now it will be seen that after the canister 1 has been filled, the cap 10 can be slipped axially directly upon the body 1, when the parts are in 70 the position shown in Figure 1, and a tight seal will then be obtained by the normal vacuumizing process as shown in Figure 2.

In order to obtain access to the contents, the seal can be broken by tension on the tab 5, whereupon the cap 10 can be readily removed.

When it is desired to replace the cap 10, this can be pushed on the body 1 so that the pips 9 come opposite a full flange portion 7, and thereby the cap is securely and frictionally held on the 80 body 1.

The groove 6 need not be a complete one, but may be in the form of small bayonet partial grooves, as shown at 13, Figure 4.

Although in the constructions described, the 85 pips 9 are shown on the cap-part, it is obvious that these may be arranged on the container-part, whilst the vertical grooves 8 may be arranged on the cap-part.

Figure 5 shows the application of the invention 90 to a rectangular container where depressions 14 on one side are staggered relatively to depressions 15 on the other side. A frictional holding of the cover on the receptacle is thereby possible by turning the cover through 180° from the position 95 where its pips coincide in disposition with the depressions 14 and 15 respectively.

I declare that what I claim is:—

1. A container including a body part having a horizontal packing flange and a neck portion 100 upstanding therefrom, said neck portion comprising a lower vertical portion adjacent said packing flange and an upper vertical portion of larger diameter than said lower vertical portion, whereby a circumferential groove is provided on said 105 neck portion adjacent said packing flange, said upper vertical portion being provided with vertical grooves which merge into said circumferential groove, and a cap part having a depending skirt portion and a flange adapted to cooperate with 110

- 5 said horizontal packing flange, said depending skirt portion having projections adapted to fit within said vertical grooves when the container is hermetically sealed and adapted to be sprung over said upper vertical portion on said neck portion when the cap part has been removed and slightly turned whereby said projections may engage the circumferential groove to provide a friction closure.
- 10 2. A container including a body part having a horizontal packing flange and a neck portion upstanding therefrom, said neck portion being provided with vertical depressions which are differentially spaced around the periphery thereof,
- 15 and a cap part having a depending skirt portion and a flange adapted to cooperate with said horizontal packing flange, said skirt portion being provided with differentially spaced projections whereby when the hermetic seal is broken, said cap part may be forced into frictional engagement with said neck portion of the body part.

3. A container including a body part having a horizontal packing flange and a neck portion upstanding therefrom, and a cap part having a depending skirt portion conforming to said neck portion and a flange adapted to cooperate with said packing flange, said neck portion having vertically directed depressions and said skirt portion having projections interengageable with said depressions when said body and cap parts are in one relative position, said depressions and said projections being asymmetrically spaced respectively about said neck portion and said skirt portion so that in another position all of said projections cannot be engaged with said depressions, and a frictional engagement of at least one of said projections is accomplished with said projection between two of said depressions.
